UNITED STATES PATENT OFFICE.

OSCAR MARION MILLER, OF LOCKRIDGE, YORK COUNTY, NEBRASKA.

WEIGHT-MOTOR.

SPECIFICATION forming part of Letters Patent No. 394,000, dated December 4, 1888.

Application filed May 12, 1888. Serial No. 273,671. (No model.)

To all whom it may concern:

Be it known that I, OSCAR MARION MILLER, a citizen of the United States of America, residing at Lockridge township, in the county 5 of York and State of Nebraska, have invented certain new and useful Improvements in Weight-Motors, of which the following is a specification, reference being had therein to the accompanying drawings.

10 This invention pertains to certain new and useful improvements in motors, having for its object the provision of simple and highly-efficient means for obtaining a rapid continuous motion or power through two series or 15 trains of gearing, the outer wheels of which revolve at a rapid rate of speed.

The invention therefore comprises the detail, construction, combination, and arrangement of parts, substantially as hereinafter 20 fully set forth, and particularly pointed out in the claim.

In the accompanying drawings, Figure 1 is a plan view of my improved motor. Fig. 2 is an end view thereof. Fig. 3 is a sectional 25 view on the line $x-x$, Fig. 1. Fig. 4 is an enlarged detail plan view.

Referring to the drawings, A designates the frame or stand in suitable journal-boxes, a, upon the end bars of which is secured a shaft, 30 a', upon which is loosely mounted the main gear-wheel B, with a tooth, a², in the outer side of which engages a tooth, a³, of a grooved pulley or drum, b, also disposed on said shaft. Around this pulley or drum is wound a rope, 35 b', one end being secured thereto, and the other end is passed, preferably, up into a tower, (not shown,) and has secured to its end a suitable weight.

The main gear-wheel B intermeshes or gears 40 with a small pinion, d, secured on a shaft, d', upon which is located a screw or worm, d². This screw or worm d² gears with a larger gear-wheel, e, of a series or train of gearing, E, located on a transverse shaft, E', and said 45 gear-wheel e gears with a small pinion, f, of a series or train, F, on a shaft, F'. This pinion f is made fast to the front face of a large gear-wheel, f², which gears with a pinion, e', fast to the front face of a second or intermediate 50 gear-wheel, e². This latter wheel gears with

a pinion, f³, fast with the central gear-wheel, f⁴, of the series F, and this gear-wheel f⁴ gears with a pinion, e³, fast with the rearmost gear-wheel e⁴ of the series E. The gear-wheel e⁴ gears with a pinion, f⁵, fast with the rearmost 55 gear-wheel f⁶ of the series F.

G is a pinion secured upon a shaft, g, said pinion being engaged by the rearmost gear-wheel f⁶ of the series F. Upon one end of the shaft g is secured a pulley, g', around which 60 is passed a belt, g², (shown in dotted lines,) or to it is connected one end of a pitman, g³, attached at its other end to a pump-handle, g⁴, or other device it is designed to operate.

To the shaft F' is rigidly secured a short 65 arm, II, whereon is placed a weight, h, held by a thumb-screw, h', working in an aperture thereof. By securing this weight at the outer end of arm II the speed of the motor will be decreased, and by securing the same near the 70 inner end of said arm the speed will be increased, as is obvious.

In practice, to wind the rope upon the pulley or drum b, the teeth a² a³ of pulley b and wheel B are thrown out of engagement, and after 75 winding said rope on said pulley and throwing the tooth a³ of the latter into engagement with the tooth a² of the main gear-wheel B motion will be transmitted to the latter by reason of the descension of the weight attached to said rope. The gear-wheel B will impart motion to the train of gearing, the gear-wheels of one series gearing with the pinions of the other series, and thus a rapid and powerful motion is given to the pulley g', which 85 will either carry the belt therewith or effect the movement of the pitman.

From the foregoing description it will be seen that I have produced an extremely simple motor, whereby a rapid continuous motion 90 is obtained, and the device, being free from all complication, is not liable to easily get out of order; and my invention also embodies advantages in point of durability, general efficiency, and inexpensiveness.

95 I claim as my invention—

The herein-described improved motor, consisting of the frame having the shafts a', E', F', and g, the series or trains of gearing E F, comprising the large gear-wheels having pin- 100

ions secured to their front faces and fast on their respective shafts, the shaft d' , having the screw or worm d^2 and pinion d , the pinion e , with which said screw or worm engages, the 5 main gear-wheel B , the pulley b in engagement therewith, the weighted rope, and the pulley g' , fast on shaft g , all combined and arranged substantially as shown and described.

In testimony whereof I affix my signature in presence of two witnesses.

OSCAR MARION MILLER.
